UNITED STATES PATENT OFFICE

GEORGE A. BENNETT, OF SAN FRANCISCO, CALIFORNIA

DESIGN FOR AN ATTACHMENT FOR THE WHEELS OF VEHICLES

Application filed June 23, 1931. Serial No. 40,307. Term of patent 7 years.

To all whom it may concern:

Be it known that I, GEORGE A. BENNETT, a citizen of the United States, residing at the city and county of San Francisco and State of California, have invented a new, original, and ornamental Design for an Attachment for the Wheels of Vehicles, of which the following is a specification, reference being had to the accompanying drawings forming part thereof.

Fig. 1 is a front elevation of a vehicle wheel attachment showing my new design.

Fig. 2 is a side elevation indicating the convex plane of the same, only a portion of the woven mesh being shown.

I claim:

The ornamental design for an attachment for the wheels of vehicles, as shown.

In testimony whereof I have hereunto set my hand this 15th day of June, 1931.

GEORGE A. BENNETT.
